UNITED STATES PATENT OFFICE.

JAMES D. O'BRIEN, OF BROOKLYN, NEW YORK.

FURNACE ATTACHMENT.

Application filed August 4, 1923. Serial No. 655,582.

To all whom it may concern:

Be it known that I, JAMES D. O'BRIEN, a citizen of the United States, and a resident of the city of New York, borough of Brooklyn, in the county of Kings and State of New York, have invented new and useful Improvements in Furnace Attachments, of which the following is a full, clear, and exact description.

10 This invention relates to improvements in furnace attachments and was primarily designed for use with boiler room furnaces.

The general object of this invention is the provision of means for collecting and 15 quenching unburned fuel, that is generally conveyed away with the ashes and escaping gases, so that it may be introduced into the furnace again.

This object is accomplished by mounting 20 at the end of the grate means for scraping the ash bed to remove the fuel therefrom, mounting in conjunction with said fuel removing means an extinguisher for receiving the fuel and quenching it, and providing in conjunction with the extinguisher means for 25 removing the quenched fuel therefrom.

This and other objects of the invention will be more clearly understood from the following detailed description and accompanying drawings.

Figure 1 is a vertical section through a furnace showing the furnace attachment in position;

Figure 2 is a vertical section along the line 2—2, Figure 1, showing the construction of the fire extinguisher;

Figure 3 is a top plan view of the furnace attachment.

Referring to the above-mentioned drawings, a furnace 10 of any well known construction provided with a chain grate 11 is shown. A fuel feeder 12 is provided for supplying fuel 13 to the chain grate 11. At the end of the chain grate the ordinary ash pit 14 is provided. The above sets forth well known furnace construction which forms no part of this invention but is merely included in order that the furnace attachment may be more clearly explained.

50 This invention includes a trough or container 16 of triangular cross section. The container 16 is carried by a plate 17 built into the rear wall 15 of the furnace. Positioned in the ends of the container 16 are bridges 18 providing slides leading from the bottom of the container to notches 19

provided in the ends of the container 16. An endless chain 20 extends longitudinally of the container 16 and is carried by the chain wheels 21 and 22 mounted outside of 60 the furnace. The chain wheel 22 is driven by a motor 23 and the chain travels through the notches 19 in the ends of the container and along the bottom of the latter. Fuel collected in the container 16 is conveyed 65 therefrom by means of the endless chain 20.

The container 16 extends transversely of the chain grate 11 and its length is approximately equal to the width of the chain grate. A fuel remover 28 fixed to a hollow shaft 70 27 trunnioned in bearings 25 and 26 mounted in conjunction with the chain wheels 21 and 22, respectively, is associated with the container 16. The fuel remover 28 is provided with a forward edge which is curved 75 to rest on the upper edge of the container 16. Extending through the inner edge of the fuel remover 28 is a pipe 29 which joins the hollow shaft 27 at 30, establishing a cooling circuit for the fuel remover 80 28. The cooling fluid is supplied to the pipe 29 through a flexible tube 31 so that the prongs may be moved freely upon the rotation of the hollow shaft 27. Mounted on one end of the shaft 27 is a crank 32 for operating it. Connected with the hollow shaft 27 is a pipe 33 leading into the container 16. A valve 34 is mounted in the pipe 33 to control the flow of the cooling fluid from the cooling circuit. The cooling fluid supplied to the pipe 29 is allowed to flow into the container 16 to act as a quenching fluid 85 35, the level of which stands at approximately the bottom of the notches 19 in the ends of the container 16.

90 The operation of this device is as follows:

When the chain grate 11 is in operation the fuel 13 is gradually carried rearward toward the furnace attachment. Generally some portions of the fuel burn more rapidly 100 than others and usually quite an amount of unburned fuel is dumped into the ash pit 14. With the attachment described above, the edge 28 is set to plow through or scrape the ash bed before the ashes are dumped 105 into the ash pit. Thus the fuel remover 28 picks from the ashes or receives from the grate the unburned pieces of fuel. This fuel remover 28 delivers these unburned pieces of fuel to the container 16 which when 110 supplied with the cooling fluid 35 forms an extinguisher or quencher for quenching the

unburned fuel. This quenched fuel is drawn from the container 16 by the endless chain 20. After the fuel has been removed from the container 16 it may be fed onto the chain grate 11.

Sparks carried forward by the escaping gases usually strike the wall of the furnace and are dropped into the ash pit. These sparks in passing down the wall of the furnace toward the ash pit drop into the container 16, are quenched, and finally are moved from the container 16 to be used as fuel.

The life of the fuel remover 28 is prolonged by the use of a cooling fluid circulated through the pipe 29 and hollow shaft. The pipe 29 also adds to the strength of the fuel remover 28.

The thoroughness with which the ashes are sifted before they pass to the ash pit 14 may be regulated to a certain extent by setting the fuel remover 28. This setting of the fuel remover 28 is controlled by the crank 32.

I would state in conclusion that while the illustrated example constitutes a practical embodiment of my invention I do not limit myself strictly to the exact details herein illustrated since manifestly the same can be considerably varied without departing from

the spirit of the invention as defined in the appended claims.

Claims:

1. A furnace attachment for removing unburned fuel from the ashes discharged by a movable grate, comprising a coal remover presenting an edge to plow through the discharged ashes to engage the unburned pieces of fuel, a receiver for the unburned fuel passing over said coal remover, said receiver having sides convergent at the bottom, a chain travelling in the angle presented by the convergent sides of said receiver, and means to conduct water through said coal remover and into said receiver. 40 45

2. In combination with a furnace provided with a movable chain grate, a receiver for the unburned fuel, said receiver spaced from said grate, an adjustable fuel remover presenting an edge for plowing through the discharged ashes to engage the unburned pieces of fuel, said fuel remover bridging the space between said grate and said receiver to pass the coal from the grate to the receiver, and means to remove the coal from said receiver; together with means to conduct water through the coal remover to said receiver, said means adapted to conform to the adjustments of said coal remover. 50 55

JAMES D. O'BRIEN.
